UNITED STATES PATENT OFFICE.

HENRY HOMER LEEDOM, OF ANDERSON, INDIANA.

ELECTRIC INSECT DESTROYER.

Application filed October 7, 1925. Serial No. 61,026.

My invention relates to electric insect destroyers of the general type wherein a plurality of lengths of electrically charged wire are disposed adjacent and parallel to each other in such a manner that the insects will be electrocuted by completing or closing the normally open circuit that is maintained, the current bridging the adjacent wires through the body of the insect that comes 10 into contact with or in close proximity to said wires.

In devices of this character, it is highly essential that the wires be properly tensioned, in order that they may be kept taut, 15 without sagging, as the proper operation of the apparatus is dependent upon the space that is maintained between adjacent wires, such space being adjusted to suit the different conditions that exist, as regards the 20 strength of current, the thickness of the wire and like considerations.

The scope of my invention extends to whatever constructions may be defined by or included within the terms or language of 25 the appended claims.

In the drawing:

Figure 1 is a plan view of my invention; Figure 2 is a side elevation thereof and

20 Figure 3 is a view in perspective of one of 25 the end members comprising the frame of my invention.

My invention, in the form or embodiment shown in the drawing and briefly described, 30 comprises a substantially rectangular frame, a plurality of relatively fine wires arranged parallel to each other, an extremely simple and novel means of retaining the wires in their relative position with respect to the frame and means for readily varying the 35 tension of the group of wires.

Referring now particularly to Figures 1 and 2, the rectangular frame indicated generally as at 10, consists of a pair of insulation members, such as wood or the like, 11 and 12, and a pair of metallic rods, 13. The insulation strips, 11 and 12, are each formed on one of its surfaces with a pair of longitudinally extending grooves or recesses, 14, of a slightly greater depth than the width 40 of each of the grooves, for a purpose to be hereinafter described.

Openings, 15 and 16, are drilled into the opposing sides of the insulation strips, 11 and 12, preferably near the ends thereof, for 45 the purpose of receiving the extreme ends 50 of the parallel rods, 13. These rods, 13, are

merely slipped into the openings, 15 and 16, formed in the insulation strips, 11 and 12, thereby providing a relatively strong construction to the rectangular frame, 10, and 60 one which may be manufactured on a high production basis. Although the rods, 13, are firmly seated within the insulation strip, 11, the opposite end of the rod is slidably mounted with respect to the insulation strip, 65 12, so that the relative length of the frame, 10, may be varied at assembly.

Adjusting screws, 17, are located through the insulation strip, 12, and arranged in axial alignment with the metallic rods, 13. 70 Nuts, 18, may be located within the cut-out portions, 19, formed on the outer end of one of the grooves, 14, as is clearly indicated in the several figures of the accompanying drawing. 75

A plurality of relatively thin wires, 20, are located upon the upper surface of the frame, 10, and extend alternately between the grooves, 14, so that each alternate wire will have a current of the opposite polarity. 80 The ends of these wires are extended downwardly into the grooves, 14, and are passed around metallic strips, 21, which are snugly fitted or wedged into the grooves or recesses, 14, as is clearly shown in Figure 1. 85

The strips, 21, have electrical connection with the binding posts, 22 and 23, by means of the leads, 24 and 25. The usual electrical house current may be supplied to the terminals or binding posts, 22 and 23. 90

For readily placing my improved electrical insect destroyer in any desired position, I provide openings, 26, in the insulation strips, 11 and 12.

In order to effectually electrocute insects, 95 such as flies or mosquitoes, immediately upon their coming in contact with any pair of wires, 20, of opposite polarity, the tensioning screws, 17, may be readily adjusted to take up the desired slack to give the entire 100 series of wires the required tension.

What I claim is:

1. In an electric insect destroyer, an open frame comprising a pair of insulation strips, each having a groove extending longitudinally thereof, a metallic strip disposed within each of said grooves, the upper edges thereof extending below the insulation strip, a plurality of parallel lengths of wires arranged between said metallic strips, and 105 means to supply the adjacent lengths of wires with current of opposite polarity. 110

2. An electric insect destroyer comprising a pair of spaced insulation strips having longitudinally extending grooves therein, rods connected between said strips, a metallic strip arranged within each of the grooves, a plurality of closely arranged wires connected between the spaced insulation strips and means for varying the tension of the said plurality of wires.
- 5 3. An electric insect destroyer comprising a pair of spaced insulation strips having

longitudinally extending grooves therein, rods connected between said strips, a metallic strip arranged within each of the grooves, a plurality of closely arranged wires connected between the spaced insulation, means for varying the tension of the said plurality of wires, and means to supply the adjacent lengths of wires with current of opposite polarity. 15

HENRY HOMER LEEDOM.
